Certificate

Patent No. D 396,832

Patented: August 11, 1998

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Chih-Huang Yang, Taichung City, Taiwan; and Ben M. Hsia, Los Angeles, CA.

Signed and Sealed this Eighth Day of April 2003.
